UNITED STATES PATENT OFFICE.

PHILIP MUELLER AND ANTON C. SCHUERMANN, OF DECATUR, ILLINOIS.

DESIGN FOR A COCK OR FAUCET.

46,032.

Specification for Design.

Patented June 30, 1914.

Application filed April 9, 1914. Serial No. 830,812. Term of patent 14 years.

To all whom it may concern:

Be it known that we, PHILIP MUELLER and ANTON C. SCHUERMANN, citizens of the United States, residing at Decatur, in the county of Macon and State of Illinois, have invented a new, original, and ornamental Design for Cocks or Faucets, of which the following is a specification, reference being had to the accompanying drawings, forming part thereof.

Figure 1 is a side elevational view, showing our new design, and Fig. 2 is a top plan view of the same.

We claim:

The ornamental design for a cock or faucet, as shown.

In testimony whereof, we have hereunto set our hands in the presence of two subscribing witnesses.

PHILIP MUELLER.
ANTON C. SCHUERMANN.
